DENNIS A. KELLOGG, OF VALPARAISO, INDIANA.

Letters Patent No. 65,679, dated June 11, 1867.

IMPROVEMENT IN WRENCHES.

The Schedule referred to in these Letters Patent and making part of the same.

TO ALL WHOM IT MAY CONCERN:

Be it known that I, DENNIS A. KELLOGG, of Valparaiso, in the county of Porter, and State of Indiana, have invented a new and useful Improvement in Monkey-Wrench; and I do hereby declare that the following is a full, clear, and exact description thereof, which will enable others skilled in the art to make and use the same, reference being had to the accompanying drawings, forming part of this specification, in which—

Figure 1 is a side view of my improved nut-wrench.

Figure 2, an edge view.

Figures 3 and 4, details of the sliding jaw.

Figures 5 and 6, sections in the line $x x$, fig. 1, in different positions of the screw-nut.

Similar letters of reference indicate like parts.

This invention relates to an improved plan of constructing a wrench for screw-taps, and consists in attaching a slotted nut to the main bar of the wrench, which bar is made narrow, with segments of screw-threads upon the edges to fit the nut. The slot in the nut is made by cutting out the threads wide enough to allow the narrow edges of the main bar to pass through them freely. The sliding jaw has two wings or projections, which are segments that fit on the flat wide sides of the main bar, and are threaded to fit in the slotted nut. By this arrangement of the parts the sliding jaw of the wrench can be moved to any point on the main bar, when the slotted nut is turned so that the narrow sides of the bar shall pass through the slot in the nut, and the jaw can be held at any point on the main bar by turning the nut so that its threaded part shall engage in the threads on the narrow sides of the main bar. Provision is also made for making the jaws of the wrench tight against a nut placed between them, as hereinafter described.

A is the main bar; B the fixed jaw, and C the sliding jaw. The main bar is made flat or narrow on two sides and wide on the other two, as shown in figs. 1 and 2. The narrow sides of the main bar are threaded for a certain distance from the handle D for a milled nut, a , which has its threads cut away on opposite sides sufficiently to permit the nut to slide freely on the main bar when the narrow sides are in the part of the nut thus cut away or slotted to allow a free passage. The sliding bar C is mortised to fit on the main bar and slide upon it, and on the part toward the handle has projecting segments $b b$ on the flat sides, as shown in figs. 3, 4, which segments are threaded to fit the screw in the nut a , as seen in fig. 2. Now, when the nut a is turned so that the slotted parts are brought over the narrow sides of the main bar, the sliding jaw C may be moved freely upon it, and it carries the nut a with it, and thus the jaws may be opened any required distance, or may be closed upon a screw-top, as shown in fig. 1.

In order to make the operation of opening and closing one of facility and certainty by the right position of the slotted nut on the main bar, a small pin, e , projects on one side, which is so placed as to catch against a shoulder on the nut a when it is turned in one direction and stop it at the point which brings the sides of the main bar in the slots in the nut, as shown in figs. 2-6; and in order to pinch the jaws tightly upon a nut the same pin e bears against an incline on the nut, when it is turned in the opposite direction, as shown in figs. 1-5. Thus the sliding jaw C may be moved quickly upon the main bar and adjusted instantly to a nut of any size. It may be secured on the nut firmly and may be released from it easily.

Having thus described my invention, what I claim as new, and desire to secure by Letters Patent, is—

A wrench constructed, arranged, and operating as and for the purpose herein set forth.

DENNIS A. KELLOGG.
